UNITED STATES PATENT OFFICE.

EMILE J. BERLET, OF RIDLEY PARK, PENNSYLVANIA.

DESIGN FOR A BADGE, EMBLEM, OR SIMILAR ARTICLE.

48,167.

Specification for Design.

Patented Nov. 23, 1915.

Application filed October 17, 1914. Serial No. 867,251. Term of patent 14 years.

To all whom it may concern:

Be it known that I, EMILE JOHN BERLET, a citizen of the United States, and a resident of Ridley Park, Pennsylvania, have invented a new, original, and ornamental Design for a Badge, Emblem, or Similar Article, of which the following is a specification, reference being had to the accompanying drawings, in which—

Figure 1, is a face view or front elevation of the article of jewelry forming the subject of my design, and Fig. 2, is a sectional view of the same, taken on the line 2—2, Fig. 1.

The structure forming the subject of my ornamental design for jewelry is in the

shape of a spoked and toothed wheel and is intended for use as a watch fob or pendant; in which case the ring shown in dotted lines will preferably be employed, or as a breast pin, brooch, hat-pin, button, cuff link, or other article of jewelry when provided with attaching means common to such articles.

I claim:

The ornamental design for badge, emblem, or similar article, as shown and described.

E. J. BERLET.
